UNITED STATES PATENT OFFICE.

JOEL GOMBOROW, OF LYNN, MASSACHUSETTS, ASSIGNOR TO GENERAL ELECTRIC COMPANY, A CORPORATION OF NEW YORK.

CENTRIFUGAL COMPRESSOR.

1,350,927.

Specification of Letters Patent. Patented Aug. 24, 1920.

Application filed November 26, 1918. Serial No. 264,221.

To all whom it may concern:

Be it known that I, JOEL GOMBOROW, a citizen of the United States, residing at Lynn, in the county of Essex, State of Massachusetts, have invented certain new and useful Improvements in Centrifugal Compressors, of which the following is a specification.

The present invention relates to centrifugal compressors comprising an impeller having blades which receive the air, or other gas being handled at their radially inner ends, impart velocity to it, and then discharge it at their peripheries to stationary discharge vanes wherein a portion of the velocity is converted into pressure.

With such a machine if we conceive a meridian plane to be passed through the center line of the impeller shaft and another plane to be passed through the middle of the impeller perpendicular to the shaft, the energy imparted to a particle of air by the rotation of the impeller may be considered to be a function of (1) the radial distance from the shaft (2) the angular distance from the meridian plane, and (3) the axial distance from the central perpendicular plane. Usually, however, impellers are built so that energy variations in an angular 25 and in an axial direction are negligible relatively to the energy variations in a radial direction; in other words, cylindrical surfaces co-axial with the shaft may be regarded nearly enough as equipotential surfaces.

30 Neglecting the effect of gravity, the energy of a particle of air within an impeller may be expressed by the formula

$$E = \frac{p}{d} + \frac{v^2}{2g}$$

where

E = energy in ft. lbs. per lb.

p = pressure in lbs. per sq. ft.

45 d = density in lbs. per cu. ft.

v = velocity in ft. per second.

g₀ = acceleration of gravity in ft. per second.

But while the total energy in a particle of air may be considered as independent of its angular distance from the imaginary fixed meridian plane, it will be apparent that unless the number of impeller blades is very large (theoretically infinite), there will be an appreciable difference of pressure be-

tween two successive blades along any given circumference concentric with the shaft. That is, the pressure will be a maximum at the driving face of a blade and a minimum at the back of it. Now, considering a case 60 where the exit edges of the impeller blades and the inlet edges of the stationary vanes are both straight and parallel to the shaft, it will be seen that at the instant an impeller blade passes a discharge vane the 65 pressure between the blade and the vane changes suddenly from a maximum to a minimum which gives rise to a considerable shock on the impeller blade, which, if the blade is not firmly anchored or stiffened, 70 may cause it to vibrate. Also since the energy along any concentric circumference is substantially constant the maximum pressure at the driving face must be accompanied by a minimum velocity of the air, and the 75 minimum pressure at the back of the blade by a maximum velocity of the air; and the sudden change of this velocity as an impeller blade passes a discharge vane gives 80 rise to an objectionable noise.

The object of the present invention is to provide an improved arrangement which will reduce the shock on the impeller vanes to a minimum and also greatly reduce the noise caused by the ends of the blades passing 85 the stationary vanes.

According to my invention I make the exit edges of the impeller blades straight or substantially straight and the inlet edges of the discharge vanes on the surface of a cylinder 90 concentric with the shaft, and I so arrange or shape the impeller blades and the vanes that such edges extend at different angles to the axis of the shaft. To this end I may make the exit edges of the impeller blades extend 95 parallel to the axis of the shaft and the inlet edges of the discharge vanes extend at an angle thereto, or vice versa; or I may make both such sets of edges extend at angles to the axis of the shaft but at different angles. 100 By this arrangement the time of the complete crossing of a blade and a vane is materially increased and the crossing is gradual so that the pressures on the vanes are varied gradually. By this means it will be seen no sudden shock will be imparted to the blades due to their passing quickly from a region of one pressure to a region of a different pressure. Preferably the arrangement is such that the ends of the impeller 110

- blades and the ends of the stationary vanes are always overlapping. In actual practice I prefer to make the exit edges of the impeller blades straight or substantially straight and parallel to the axis of the shaft, and to make the inlet edges of the discharge vanes on the surface of a cylinder concentric with the shaft but with these edges inclined at an angle to the axis of the shaft.
- 10 In the drawing, Figure 1 is a side elevation of a portion of a centrifugal compressor embodying my invention and Fig. 2 is a developed top plan view looking down on Fig. 1.
- 15 Referring to the drawing, 5 indicates a shaft carrying an impeller which is provided with blades 6. As shown, the exit edges of these blades are straight and parallel to the center line of the shaft. Surrounding the 20 impeller are the stationary discharge vanes 7 which are suitably shaped and their inlet edges set at an angle to the center line of the shaft. The radially inner edges of the discharge vanes 7 are thus inclined to the radially outer edges of the impeller blades 6 and as a result a blade does not pass a vane throughout its axial width at the same instant but passes it gradually. As a result 25 both the shock on the blade and the noise are materially reduced.
- 30 In accordance with the provisions of the patent statutes, I have described the principle of operation of my invention, together with the apparatus which I now consider to represent the best embodiment thereof, but I desire to have it understood that the apparatus shown is only illustrative, and that the invention can be carried out by other means.
- 35 40 What I claim as new and desire to secure by Letters Patent of the United States, is:—
1. In a centrifugal compressor, an impeller having a set of blades and a set of discharge vanes which surround the impeller, 45 said discharge vanes having substantially the same axial width as the blades and extending radially and circumferentially whereby the fluid discharged to them from the blades is given a combined radial and tangential path, said vanes serving to convert velocity into pressure, the discharge edges of the blades and the inlet edges of the vanes being straight and made to extend at different angles to the axis of the shaft whereby they will cross each other gradually. 50
2. In a centrifugal compressor, an impeller having a set of blades and a set of discharge vanes which surround the impeller, said discharge vanes having substantially the same axial width as the blades and extending radially and circumferentially whereby the fluid discharged to them from the blades is given a combined radial and tangential path, said vanes serving to convert velocity into pressure, the edges of said sets being straight and arranged with the edges of one of said sets parallel to the axis of the shaft and the edges of the other of said sets at an angle thereto, whereby they will pass each other gradually. 55
3. In a centrifugal compressor, an impeller having a set of blades and a set of discharge vanes which surround the impeller, said discharge vanes having substantially the same width as the blades and extending radially and circumferentially whereby the fluid discharged to them from the blades is given a combined radial and tangential path, said vanes serving to convert velocity into pressure, the discharge edges of the impeller 60 blades being substantially parallel to the center line of the shaft, and the inlet edges of the discharge vanes being set at an angle thereto. 65
4. In a centrifugal compressor, an impeller having straight blades set substantially parallel to the center line of the shaft, and stationary discharge vanes which surround the impeller and extend radially and circumferentially whereby the fluid discharged to them from the impeller is guided in a combined radial and tangential path, said discharge vanes having their radial inner edges extending at an angle to the center line of the shaft. 70
- 75 In witness whereof, I have hereunto set my hand this 16th day of November, 1918.
- JOEL GOMBOROW
